AUTOMATIC FLUID COOLED GRATE

George W. Wallace, East St. Louis, Ill.

Application May 2, 1938, Serial No. 205,416

3 Claims. (Cl. 122—376)

This invention relates to an improved automatic fluid cooled grate and has for its principle object to provide a satisfactory grate which may be used as an integral part of an apparatus for carbonizing and distilling coals, lignites, oil shales or similar carbonaceous materials, by direct contact with hot gases passing down through the same.

Another primary object is to provide an automatic grate or stoker, which may be used to burn coal or other fuels at a high rate of combustion under severe temperature conditions.

Still another object is to provide a grate which is adapted to combining the operations of destructive distillation and combustion without requiring a separate grate, carbonization and combustion chamber.

A still further object is to provide a satisfactory water cooled grate bar which may be used in a grate assembly consisting of a plurality of such grate bars.

A further object is to provide a grate for the above purposes which is comparatively inexpensive to install and which will not blister, become damaged, or burn out as quickly as other types of grates or stokers which are not water cooled.

Other objects and desirable features of the invention will be hereinafter pointed out.

In the present invention the preferable arrangement of the automatic grate comprises a plurality of reciprocating grate bars which are water cooled internally and which are arranged within a suitable carbonization or combustion chamber and which are adapted to move and support the material, being carbonized or burned, into and through the chamber.

Figure 1 of the drawings is a vertical sectional view of one type of water cooled grate bar that may be used in practicing the present invention.

Figure 2 is a vertical cross section on line 2—2 of Figure 1, showing rectangular water channels or passages through the grate bar.

Figure 3 is a vertical sectional view of a slightly different type of water cooled grate bar which may be used in the grate assembly of the present invention.

Figure 4 is a vertical cross section on line 4—4 of Figure 3, and shows round water channels or passages cast into the grate bar.

Figure 5 is a vertical sectional view of a water cooled grate bar which may be used in which the arrangement of the water channels is slightly different.

Figure 6 is a vertical cross section on line 6—6 of Figure 5.

Figure 7 is a vertical sectional view of still another type of water cooled grate bar which may be used in a water cooled grate assembly and shows a single large water channel or passage cast into the bar.

Figure 8 is a vertical cross section on line 8—8 of Figure 7.

Figure 9 is a broken view in plan of a portion of a grate assembly showing the grate bars in the position occupied after advancing fresh material into the chamber.

Figure 10 is a broken view in plan of the grate assembly, Figure 9, showing two grate bars pulled out.

Figure 11 is a view in plan of the grate assembly, Figure 9, showing five of the grate bars pulled out.

Figure 12 is a view in plan of the grate assembly, Figure 9, showing all of the grate bars pulled out and in position to feed fresh material into the chamber.

Figure 13 is a vertical sectional view of the water cooled grate housed within a carbonizing chamber on line 13—13 of Figure 14.

Figure 14 is a vertical section on line 14—14 of Figure 13.

Referring to the drawings in which all numerals refer to similar elements and which illustrate the preferred form of the present invention in which the automatic water cooled grate consists of a plurality of water cooled grate bars similar in type to the bars illustrated in Figures 1 to 8 inclusive. Figures 1 and 2 show a metal grate bar 1 provided with channels or passages 2 and 3 which are connected at the end of the bar by return bend 6 through which water is caused to circulate. The water supplied to the grate bar

40 is regulated by valve 4 passing through flexible connections 5 (in the illustration a flexible hose) into and through the upper channel 2 at the front end of the bar, and is returned through the lower channel 3 by return bend 6 and flexible connection 7 to manifold discharge 8. The grate bar is provided with a raised vertical or nearly vertical feeding face 10 for pushing the material being carbonized or burned into the carbonization or combustion chamber from hopper 11. The upper surface of the grate bar 12 forms a seal with the front of the hopper 11. As shown in

Figure 1 the grate bar is pulled out. Any suitable means for reciprocating the plurality of grate bars may be used for instance in Figure 1

55 a rack 13 which is moved back and forth by seg-

ments of pinion gears 14 and 15 is shown. The grate bar may be inclined near the rear end 16 if desired for the purpose of increasing the depth of material on the grate.

A slightly different grate bar is shown in Figure 3 which may be used if desired in the grate assembly, in this illustration, the bar is stepped down one or more places 17 for the purpose of loosening the material passing through the chamber on the grate and in this illustration the grate bar is shown as being moved by a double acting cylinder and piston 18 which may be actuated by water, oil, steam, or air pressure.

The cooling water may be circulated through the grate bars in any practical manner, for instance the upper and lower water channels may extend through the bars and be connected at the rear end with a return bend 6 as shown in Figure 5 or a single channel or passage may extend through the bar as shown in Figure 7, in this case the water enters through flexible connection 5 at the front end and is discharged through flexible connection 7 into manifold 8 at the rear end of the grate bar. The water used to cool the grate bars may be recirculated from a suitable container either by pumping or by gravity, or the water leaving through manifold 8 may be used for other purposes and fresh water supplied to the cooling channel or channels in the grate bars through valves 4 and connections 5.

The grate bars may be made of any suitable metal or alloy and the channel or passages provided for circulating water may be formed in any suitable manner; one method which has been found to be satisfactory is to cast the grate bar around pipe or tubing of the desired size and shape, or alternately the channel may be formed in a casting by using a core of the desired shape.

In utilizing the present invention in its preferred form a plurality of water cooled grate bars are arranged to form a grate of the desired length, width and area, and suitable means are provided for moving the individual bars back and forth. Among the possible means two practical methods have been shown in the drawings.

In the preferred method of operation all of the grate bars are moved in toward the rear of the carbonization or combustion chamber at the same time and speed, the raised faces 10 of the grate bars remove a regulated amount of material from hopper 11 which is carried on the grate bars 1 into the chamber.

Figures 1, 3, 5, and 12 show the grate bars pulled out and in position to move in, toward the rear of chamber, with fresh material.

After the grate bars have moved in they are brought out in sequence, no two adjoining grate bars being moved out at the same time. Figure 9 shows all of the grate bars in the position occupied after moving a fresh supply of material into the chamber. Figure 10 shows the first move following delivery of fresh material into the chamber, here two grate bars C and F have been moved out with two stationary grate bars on each side. The second move is shown in Figure 11, here three more grate bars A, D, and G have been moved out. The final move is shown in Figure 12, here grate bars B, E, and H have been moved out and the grate assembly is shown in position for moving all the bars in simultaneously with fresh material. With this operating cycle the material on the grate is not drawn back when the grate bars are moved out and any disturbance of the material is reduced to a minimum.

The present invention provides a grate which

makes it possible to carbonize coal, lignite, oil shale or like carbonaceous materials continuously, by causing hot gases to pass down through a body or layer of the material as it passes through a carbonization chamber supported on and moved by the water cooled grate hereinabove described.

Where the invention is used for the purpose of carbonizing, the grate 1 is housed within a suitable carbonizing chamber such as the chamber shown in Figures 13 and 14 of the drawings, in which 20 shows one form of carbonization chamber which would be suitable for the purpose, 21 represents an inlet or inlets for the hot gases used to effect the carbonization, a space 22 is shown which may be used as a temperature equalizing chamber, or if desired as a combustion chamber. Any suitable type and character of hot gases may be used at any temperature that is practical.

One or more receptacles or cells are provided below the grate into which the products of the carbonization along with the hot gases used to effect the carbonization are drawn by a partial vacuum or are forced under a slight pressure, in the drawings Figure 13 five cells, 23 to 27 inclusive are shown for this purpose.

The gases and products leave the carbonizing apparatus through a series of valves 28 which regulate the quantity of hot gases passing down through the material and grate into any one of the receptacles or cells, this regulation makes it possible to control the carbonization at a number of different places in the material. The valves 28 connect with gas manifold 29 which connects with a gas exhauster. The material is fed from hopper 11 onto the grate and through the chamber the residue of the carbonization being discharged into hopper 30.

This arrangement permits the use of a grate having a large area and provides a rapid and economical method of carbonizing a large tonnage of semi-bituminous coals, lignites or oil shales as it provides a grate which will withstand the temperatures required and used in an operation of this character. Grates which are not cooled may operate for a short time without trouble or replacements but must be operated at a temperature below that required for greatest efficiency. With the present grate the temperature of the gases passed down through the same at any one point may be as high as is required without danger to the grate and the regulation can be made to suit the carbonizing reactions instead of being restricted to that required to protect the grate.

The grate of the present invention is suitable for use in my co-pending application No. 204,048.

Where the grate is used for combustion purposes in a power plant it will be arranged in a combustion chamber in the usual manner. The area of the grate will be determined by the size of the boiler installation and fuel requirements of the combustion chamber. Cells may be provided under the grate to furnish a distributed supply of air under a forced draft of regulated intensity. The grate and cells shown in Figure 13 would be similar to the arrangement required for combustion, the cells in this case being used to regulate the air supplied below the grate to the different parts of the fire bed.

The water cooled grate of the present invention may be used to accomplish another novel operation. It may be used in an apparatus designed to combine the operation of destructive distillation or carbonization and combustion in

one operation as follows: The material to be destructively distilled and burned is fed onto the grate and through the combustion chamber in the manner hereinabove described and burned in the usual way using forced draft, or if desired, natural draft; however, in this dual operation, the first cell 23 or cells 23 and 24 Figure 13 at the front or feed end of the combustion chamber are connected with a gas exhauster and a partial vacuum is carried in these cells which will draw a controlled amount of the hot combustion gases from the combustion chamber down through the fuel as soon as it enters the chamber in this manner a large percentage of the oils and gases usually formed or resulting from the destructive distillation of carbonaceous fuel materials will be produced and after condensing the oils the gaseous products may be returned to the combustion chamber. Cells 25, 26, and 27 Figure 13 with additional cells if required, are used to furnish the air required under forced or natural draft, to complete the combustion of the fuel after it has passed through the distillation zone. Such a dual operation could not be carried on in the manner described without using a water cooled grate such as the grate constituting the present invention.

Utilizing the above described dual operation a large quantity of oil can be recovered from coals or lignites at low cost as a by-product in the manufacture of power which in many localities would be a very important matter. Where oil shales are distilled this dual application may be of great value to the localities where oil shale deposits occur. Normally when oil shale is distilled the waste heat and gases including the free carbon in the spent shale is lost. The use of the present grate in the combined distillation and combustion apparatus will permit the extraction of the oil from the shale and the conversion of the waste and other heat values of the shale into power. The combustible matter in the spent shale will be completely burned, leaving a shale residue which from certain shales gives an added value to the products. A water cooled grate such as the grate of this invention is essential for such an operation.

Any required number of grate bars may be used in a grate assembly, however in practice four bars would probably be the minimum number used and in this case the two outside bars might be stationary if desired. Where a relatively small number of bars are used they may be installed in a well or retort provided with air tuyères along the sides of the grate.

In the drawings the grate is shown in a horizontal position. With some materials and depending on the products produced the grate may be inclined from the front to the back. Where the material has a tendency to move with difficulty through the chamber the grate would be inclined down. It is conceivable, that where a non-uniform thickness of material is desired, that the grate might be inclined up.

In the preferred form of assembling a plurality of reciprocating water cooled grate bars

has been described in detail; however, the method of feeding the material onto the grate and through the carbonization or combustion chamber may be varied from the preferred method, for instance a separate feeder may be used to move the material which feeder would have the same action as the feeding faces of the grate bars as shown in the drawings or a series of plungers or rams may be used for the purpose each of which would be arranged to feed material to one or more grate bars. With a different method of feeding material into the carbonization or combustion chamber the movement of the grate bars could be arranged in a different sequence to that shown in the drawings.

Ordinarily the most practical way of cooling the bars of the grate would be by circulating water through the same, however, in some instances it may be desirable to circulate another fluid, or under unusual circumstances where the cooling required is small, air or gases may be circulated.

Other uses for a water cooled grate of the character described exist and further uses will be developed. However, the several important uses described in the above specification represent the principle applications of the invention.

I claim:

1. In the destructive distillation and combustion of a layer of fuel materials passing through a combustion chamber, a water cooled grate comprising a plurality of separately mounted individually reciprocating grate bars each of which is provided with an internal channel through which water is circulated, said grate being arranged to receive, support, and move the material through the combustion chamber over a series of separate cells over which the material passes, the first cells being under suction and the rest used to supply air to the material under forced draught.

2. A carbonizing retort comprising a combustion chamber having a plurality of longitudinally spaced transversely extending separate cells, some of which are under suction and others of which are under forced draft, a reciprocable grate mounted upon and extending in closurewise relationship over said cells, the grate having longitudinally spaced apertures, each of which is normally disposed in registration with one of said cells, said apertures being of such size and position in relation to the cells as to be shifted into registration with a different cell upon reciprocation of the grate.

3. In a carbonizing retort of the character described, a grate consisting of a plurality of longitudinally shiftable grate bars each having an internal fluid-circulating cooling channel having longitudinally extending spaced legs connected at one end by a reverse bend, one of said channels being connected at its other end by means of a flexible tube to an individual source of cooling fluid and the other channel being connected by flexible tubing to a discharge manifold common to all of the grate bars.

GEORGE W. WALLACE.
